UNITED STATES PATENT OFFICE.

FRANK GADE, OF CHICAGO, ILLINOIS.

RADIATOR ATTACHMENT.

1,417,312.

Specification of Letters Patent. Patented May 23, 1922.

Application filed November 21, 1921. Serial No. 516,760.

To all whom it may concern:

Be it known that I, FRANK GADE, a citizen of the United States, residing at Chicago, in the county of Cook and State of Illinois, 5 have invented new and useful Improvements in Radiator Attachments, of which the following is a specification.

This invention relates to gage attachments for motor-vehicle radiators designed to indicate the water level in the same, and the invention has for its object to provide a novel and improved attachment of this kind which gives a signal when the water level goes down to such an extent that a replenishing of the water supply becomes imperative to prevent overheating of the motor and damage to the radiator.

The object stated is attained by means of a combination and arrangement of parts to be hereinafter described and claimed, and in order that the same may be better understood, reference is had to the accompanying drawing, wherein:

Figure 1 is an elevation of the device in place on a radiator, and Fig. 2 is a central vertical section thereof.

Referring specifically to the drawing, 5 denotes a fragment of the upper tank of an ordinary motor-vehicle radiator, the same being provided with the usual filler neck 5^a provided with a closure 6 of the conventional type of screw cap.

In the top of the cap 6 is a central aperture in which seats a nipple 7 having above the cap an outstanding annular flange 7^a by means of which there is clamped to the top of the cap an ornament 8 having the form of a crown. Below the top of the cap the nipple 7 carries a fastening nut 9 and a lock nut 10 for the latter, the nipple being exteriorly threaded for this purpose. The nut 9 screws against the under side of the cap to hold the ornament 8 firmly clamped between the flange 7^a and the top of the cap.

45 The ornament 8 is surmounted by an indicator 11 having the form of a Greek cross which is carried by a light tubular shaft 12 passing through a central aperture in the top of the crown-like ornament 8, with a thin washer 13 and a cross pin 14 beneath the latter to prevent the tube from rising. Beneath the top of the crown 8, the shaft 12 has diametrically opposite longitudinal slots 15 and extends into a tubular shaft 16 which 55 passes downwardly through the nipple 7 into the tank 5 a sufficient distance to dip into

the contents of the latter. The shafts 12 and 16 are free to rotate, and they are connected to turn together by a cross pin 17 passing through shaft 16 and through the 60 slots 15 of shaft 12. The two shafts are also loosely or telescopically connected, the shaft 16 being free to slide upwardly on shaft 12 to the extent of the length of the slots 15, the pin 17 seating loosely in said slots. 65

On the lower end of shaft 16 is fastened a float 18 having a spirally fluted exterior so that it may also operate as an impeller for giving a rotary motion to the shaft 16.

When the water level in the tank 5 is normal, the float 18 locates the shaft 16 high up on the shaft 12, and shaft 16 seats over the slots 15 to close the same. As the water level goes down, the float 18 follows until the cross pin 17 reaches the bottom of the 75 slots 15. If the water level continues to go down, the float is left suspended above the same, and the steam rising from the water and operating against the fluted exterior of the float 18 causes the same to rotate and to 80 spin the shaft 16, this motion of shaft 16 being communicated to shaft 12, and as the shaft 12 carries the indicator 11, the latter is whirled around, thus notifying the driver of the fact that the water level in the radiator 85 has reached the danger point. The upper end of the shaft 16 acts to indicate ordinary fluctuations of the water level in the tank 5 so that the driver may observe whether the radiator needs water. If, through negligence, or otherwise, the water is allowed to 90 reach a dangerous low level, the hereinbefore described rotary motion of the float 18 takes place to operate the indicator 11.

The attachment is very simple and highly 95 efficient, and it can be easily applied to any ordinary radiator cap; or the cap may be part of the device.

I claim:

1. A water-level indicator comprising a 100 support, a shaft rotatably and slidably carried by the support, an indicator carried by the shaft, and a float fastened to the lower end of the shaft, and having an impeller shape.

2. A water-level indicator comprising a support, a tubular shaft rotatably and slidably carried by the support, an indicator, a tubular shaft carrying the indicator, a connection between the shafts for permitting 110 their rotation together and a sliding movement of the first-mentioned shaft relative to

the second-mentioned shaft, and a float carried by the first-mentioned shaft and having an impeller shape.

3. A water-level indicator comprising a support, a tubular shaft rotatably and slidably carried by the support, an indicator, a tubular shaft carrying the indicator, and provided with longitudinal slots, a cross pin carried by the first-mentioned shaft, said shaft slidably fitting the second-mentioned shaft, and the cross pin seating in the aforesaid slot, and a float carried by the first-mentioned shaft and having an impeller shape.
- 15 4. A water-level indicator comprising a support, a shaft rotatably and slidably car-

ried by the support, a rotatable indicator to which the upper end of the shaft is operatively connected, said connection being a sliding one, means for limiting the downward sliding movement of the shaft, and a float fastened to the lower end of the shaft and having an impeller shape.

5. A water-level indicator comprising a support, a shaft rotatably carried by the support in pendent position, an impeller on the lower end of the shaft, and a rotatable indicator to which the upper end of the shaft is operatively connected.

In testimony whereof I affix my signature. 30

FRANK GADE.
